UNITED STATES PATENT OFFICE.

HALBERT B. HALVORSEN, OF CHICAGO, ILLINOIS, ASSIGNOR TO SULLIVAN MACHINERY COMPANY, A CORPORATION OF MASSACHUSETTS.

PUMPING SYSTEM.

Application filed April 8, 1919, Serial No. 288,501. Renewed April 19, 1924.

My invention relates to pumping systems, and more especially to a controlling means for automatically controlling the operation of one or several pumping units of a system.

5 One object of this invention is to provide an improved controlling means for a fluid pumping unit, and more especially a controlling means which is applicable to pumping units of the pneumatically operated, or 10 air lift type. Another object is to provide an improved controlling means for controlling a pumping unit having an automatically operated starting means, such for example as is disclosed in copending application 265,226, 15 filed December 4th, 1918, patented June 24, 1924, #1,499,315. These and other objects and advantages of my improved construction will, however, hereinafter more fully appear.

In the accompanying drawings I have 20 shown for purposes of illustration several embodiments which my invention may assume in practice.

In these drawings,—

Fig. 1 is a side elevation of a pumping system provided with my improved controlling means, certain parts being shown in section.

Fig. 2 is a plan view thereof showing three pumping units.

30 Fig. 3 is a longitudinal sectional view on line 3—3 of Fig. 2.

Fig. 4 is an enlarged detail sectional view of the auxiliary pump shown in Fig. 1.

Fig. 5 is an enlarged detail sectional view 35 of the controlling means for the auxiliary pump.

Fig. 6 is a side elevation, partly in section, of a modified form of pumping unit.

Fig. 7 is a side elevation, partly in section, 40 of still another modification.

Fig. 8 is a longitudinal sectional view, on an enlarged scale, of the auxiliary pump shown in Fig. 6.

Fig. 9 is a longitudinal sectional view of a 45 pilot valve.

Fig. 10 is a detail of one of the elements of the pilot valve.

Referring to the drawings, I have there 50 shown for the purpose of illustrating the principal features of my invention, a pumping system comprising a series of pumping units and a compression unit, although, as obvious, only one pumping unit may be used and the source of power may be taken from 55 a pipe line instead of directly from a com-

pression unit as shown. In the forms shown the compression unit comprises a compressor 1, a cylinder 2, preferably provided with the usual unloading mechanism, and a receiver 3. A supply pipe 4 is connected to the receiver 60 and also to branch lines 5, each of which preferably conducts the pressure fluid, or operating fluid, to a single pumping unit, as shown clearly in Fig. 2. A T coupling 7 is provided in the inlet pipe line 5, and a pipe 65 line 6 leads from a lateral opening therein to an automatic auxiliary starter controller mechanism, which will be hereinafter described. The inlet supply pipe for the individual pumping unit preferably terminates 70 in a pipe 8, which conducts the pressure fluid to the down pipe, which feeds the main pump.

A main controlling valve may be placed in the pipe line or main 4, for controlling all 75 of the pumping units simultaneously, but preferably I provide a controlling valve in each of the pipe lines 5, and preferably between the main 4 and the coupling 7. Any 80 form of controlling valve desired may be used, but I preferably provide a valve 9 of the semi-balanced valve type, having a reverse web 10 as shown in Fig. 1. This valve is provided with aligned differential valve 85 seats 11 and 12 in the web 10 cooperating with differential valve heads 13 and 14, of which the head 14 is the larger, mounted on the same valve pin 15. In the form shown, the valve pin 15 projects upwardly through a guide 16 mounted on the casing of the 90 valve 9, the valve pin 15 preferably having a pivotal connection as shown at 17 with one end of an operating or controlling lever 18 which is preferably horizontally disposed. The controlling arm 18 is fulcrumed adjacent this end on a support or bracket 19 which is preferably mounted directly on the valve pin guide. A weight 20 is adjustably 95 mounted on the controlling arm 18 and normally tends to raise the valve to open the latter and as is obvious, the weight 20 may be shifted along the arm 18 to vary the moment of the weight about the fulcrum and so vary the force which normally tends to open the valve. The pressure fluid in the main 4 acting on the larger valve head 14 tends to hold the valves shut, and the moment of the weight 20 is so regulated that normally the fluid pressure acting on the differential valve will hold the valve shut until some 100 105 110

force is added to the moment of the weight 20 to open the valve. In the form of my invention herein, this added force comprises a float controlled mechanism which functions to open and close the valve in accordance with the variation of the liquid level in a receiving tank.

This float controlled mechanism is preferably attached pivotally to the free end of the controlling arm 18, a vertically disposed rod 21 constituting the means of transferring the controlling action of the float to the valve mechanism above described. A plurality of spaced stops 22 and 23 are secured to the rod 21 and a float 24 preferably of the diving bell type is mounted freely on the rod between the stops in such a manner that as the liquid level in the receiving tank rises, the float 24 will be carried upward against the upper stop 22 and will engage the latter with sufficient force to counteract the excess moment of the weight 20 and close the valve. As the liquid level in the receiving tank falls, the float 24 will slide down the rod 21 into contact with the stop 23, but during this interval, the valve will stay closed because the moment of the weight 20 is not sufficient to overcome the action of the fluid pressure on the differential valve heads. After the float 24 has come into contact with the stop 23 and the level of the liquid has fallen sufficiently to permit a part of the weight of the float to form a moment to be added to that of the weight 20, these added moments will be sufficient to open the valve and permit a flow of fluid pressure to the pumping mechanism.

If a plurality of pumping units are operated to refill the tank, these pumping units may be operated simultaneously by a single or a plurality of simultaneously acting float controlled means, but I preferably place the stops 22 and 23 at different levels on the controlling rods 21 so that these floats will successively engage the upper or the lower stops so as to successively operate or stop the pumping units. This form of controlling mechanism is best shown in Fig. 3, wherein a plurality of floats 24, 25, and 26 are shown mounted within baffling casings 27, 28, and 29 in a reservoir 30, the casings serving to prevent the surging of the water in the receiving tank or reservoir from affecting the floats to cause the latter to rapidly reciprocate the controlling rods 21 and thereby cause the valve controlled thereby to flutter.

It will be noted that a large heavy float 24 is not required since the moment of the weight 20 can be so regulated that only a small additional weight is necessary to unseat the valve 9, but if desired, a large float may be used and the weight 20 may be dispensed with. The spacing of the stops 22

and 23 also prevents a fluttering of the valve for the valve will not be operated during the interval of time during which the float is traversing the space between the stops, this being advantageous because, as is obvious, if the float were attached positively to the controlling rod 21, a small rise or fall in the liquid level would operate the valve and the latter would be caused to oscillate rapidly as the liquid is pumped in the tank or withdrawn therefrom.

In my preferred form of pump controlling means, I also provide between the main 4 and the T 7 and preferably between the valve 9 and the T 7, a reducing valve 31 of any type, but herein shown of a common type of spring pressed, reducing valve having a centrally apertured web 32, a valve head 33 adapted to seat thereon to stop the flow through the aperture therein; a spring 34 which normally tends to seat the valve and an adjustable cap 35 for closing the opening through which the valve and spring are inserted and abutted on opening of the valve by the stem of the latter with the result that its position controls the degree of valve opening and thereby the area of the flow passage past said valve. Of course the spring tension is also varied on movement of the cap, but this is immaterial within the range of operation as the spring pressure should be comparatively light. When the valve 9 is opened to permit a fluid flow to the pumping apparatus, the reducing valve 31 will normally maintain a constant difference in pressure between the inlet side thereof and the outlet side thereof for a purpose to be hereinafter more fully disclosed. It should be noted that the function of the valve mechanism 31 is not that of the usual "reducing valves"; so-called, in which a constant discharge despite variable fluid supply or constant discharge despite varying fluid consumption are the primary functions, but rather that of a choke valve and the substantially constant pressure difference between the pipes 5 and 8 maintained during normal pumping is due to the facts (1) that during normal pumping the discharge conditions at the foot piece are relatively constant and (2) that the foot piece orifices have a considerably larger aggregate flow area than the flow area past the valve 33 even when the latter is fully open, whereby a substantial but approximately constant pressure reduction occurs.

The pressure fluid from the outlet side of the reducing valve is conducted, in the form of my pumping means disclosed in Fig. 1, through a cap 36 to the inside of a large down pipe 37 which feeds the main pump, not shown, the liquid pumped being forced upward through a riser 38 to a receiving tank 39 wherein the liquid and pressure

fluid are separated, the liquid flowing through a pipe 40 to the reservoir 30. Under certain conditions, when a pumping apparatus is left idle for a period of time, the liquid to be pumped flows into the well to a higher level, as denoted at A, than is normally maintained during pumping operation. The level normally maintained during pumping operation is denoted at B, and the excess head of water A-B which has formed during the idle periods of the pump creates a static head which prevents the operation of the main pump. To overcome this difficulty, I preferably provide an auxiliary starting pump 41, which, in the form of my invention shown in Fig. 1 is mounted on the riser 38 at about the level B and consists of a separate fluid pumping means actuated by a separate supply of pressure fluid. This pumping means, as is shown in Figs. 1 and 4, preferably comprises a hollow footpiece 42 having a threaded connection with the adjacent sections of the riser 38 and having on one side thereof a hollow boss 43 to which is connected a pipe 44 for supplying pressure fluid to this pump. The pressure fluid from the pipe 44 flows into the hollow interior 45 of the hub 43, from there to an annular chamber 46 which surrounds a centrally disposed cylinder 47, and passes through openings 48 formed in this cylinder into the fluid to be pumped, emulsifying, and elevating the latter in a well known manner.

35 The flow of pressure fluid through the pipe 44 to the auxiliary or starting pump 41 is preferably automatically controlled so that this flow occurs only at such times as the static head A-B is present to prevent the operation of the main pump. In the form of my invention shown, this flow is controlled by a valve 49 shown herein as similar to the valve 9 and as having a weight 50 which normally tends to close the valve 49 instead of open it as does the weight 20.

Referring to Figs. 1, 2, and 5, but more especially to Fig. 5, the controlling means shown preferably consists of a cylinder 51, a piston head 52 reciprocable therein and attached to a valve controlling rod 53 by means of a sleeve 54, and an adjusting nut 55, the latter being operable to adjust the relative position of the piston head 52 to the valve 49 to vary the control of this valve. 55 When pressure is admitted to the cylinder 51 to raise the piston 52 and open the valve 49, the pressure fluid will flow to the pipe 44 to operate the starting pump and as this pump functions to remove the excess head A-B, the flow through the pipe 44 will increase and the pressure in the cylinder 51 will drop. To prevent the closure of the valve 49 upon a drop of pressure in the pipe 44 before all of the head A-B is removed, I preferably provide means for holding the

controlling rod 53 in an elevated position during an interval of time sufficient for the removal of the excess head. In the form shown herein, this valve rod retaining means consists of a cam lever 56 adapted to engage the sleeve 54, a cam lever operating piston rod carrying on one side of the cam lever a collar 58 attached to the rod 57, and a spring 59 abutting against an adjustable stop 60, the spring 59 tending to force the piston rod 57 and the collar 58 downward to engage the cam lever to release the sleeve 54 and thereby permit the valve 49 to close. Mounted on the opposite end of the rod 57 is a piston 61 reciprocable in a cylinder 62 under the influence of pressure fluid admitted at the lower end of this cylinder. When the pressure fluid admitted to this cylinder 62 is sufficient to overcome the force of the spring 59, the piston rod 57 and the collar 58 will be moved upward to free the cam lever 56 and a small spring 63 will then be free to force the cam lever up into engaging position with the sleeve 54. This spring 63 is preferably very light so that the sleeve 54 may be moved upward past the cam even when the cam is forced into engaging position by this spring, but the sleeve 54 will automatically lock itself by engagement with the cam surface of the cam lever until the pressure fluid in the cylinder 62 falls sufficiently to permit the heavier spring 59 to move the cam lever 56 from engaging position.

Fluid pressure may be admitted to the operating cylinders 51 and 62 in a variety of ways, but I preferably use a plurality of pipes 64 and 65 connected to the pipe 6, the pipe 64 preferably branching from the pipe 65 as shown in Fig. 1 and conducting pressure fluid directly from the pipe line 6 to the cylinder 62. The flow of fluid from the pipe 65 to the cylinder 51 is preferably controlled by a pilot valve 66 which is shown herein (see Fig. 9.) as of the Judson type. Since these valves are well known, it is not necessary to go into a detailed description of the construction or operation of this valve. It may be stated that such a valve is fully shown and described in the patent to one J. L. Osborne, No. 1,141,975, granted June 8, 1915, and that in the position of the parts shown in Fig. 9, a fluid flow from the pipe 65 to the pipe 76 leading to the cylinder 51 is prevented by a disc 67 which closes an aperture 68 in a hollow valve member 69, the disc 67 and valve member 69 being held in a depressed position against the action of springs 70 and 71 respectively by a heavy spring 72 acting against a diaphragm 73, the tension of the spring 72 being adjusted by an adjustable cap 74. In this position of the parts, any excess pressure in the pipe 76 is exhausted to the atmosphere through an 130

aperture 75 in the lower part of the valve. When the pressure in the pipe lines 6 and 65 becomes sufficient to overcome the tension of the spring 72, the springs 70 and 71 force the valve members 67 and 69 upward, thereby closing the exhaust passage 75 and permitting a flow of pressure fluid from the pipe line 65 through the passageway 68 and the pipe line 76 to the lower side of the piston 52 in the cylinder 51 to open the valve 49. The manner in which this flow occurs will be evident, for when upward movement of the member 67 is stopped with the latter in a position to close the apertures 75, the member 69 continues to move upward and opens a space between its lower end and the upper surface of the member 67 through which fluid may pass from passage 68 to and through the usual annular series 20 of ports in the member 67 (see Fig. 10). During the normal operation of the system, receiver pressure will exist in the receiver 3, pipe main 4, and the pipe lines 5 up to the reducing valves 31, and between 25 the reducing valves 31 and the main pumps the pressure will be less than receiver pressure but will be sufficient to operate the main pumps under normal conditions. This latter pressure, I preferably term the operating pressure. When the pumping units have 30 remained idle for a period of time sufficient to permit an excess head as A—B to form and the valve 9 is opened to permit a flow of pressure fluid to the main pump to start 35 the pumping operation, the operating pressure in pipe lines 8 and 37 will not be sufficient to operate the main pump against the excessive static head existing in the riser pipe 88, and neither in fact would the full 40 pressure in line 4. There will then be no pumping action and no flow of fluid through the pipe line 8 so that the pressure in the pipe 8 will increase on flow past the reducing valve 32 until the pressure in the pipe 45 begins to approach receiver pressure. At some point between the operating pressure and the receiver pressure, the pressure fluid admitted to the cylinder 62 will raise the rod 57 and permit a movement of the cam 56 into locking position under the influence 50 of spring 63. At a yet higher pressure but preferably less than receiver pressure, the tension of the spring 68 in the Judson valve will be overcome and pressure fluid will be admitted by this valve to the cylinder 51 to open the valve 49. Flow will then start 55 to the auxiliary or starting pump 41 and the fluid flow through the pipe 44 will remove the excess head. As the flow starts 60 through the pipe 44 and pump 41, the pressure in pipe lines 6 and 65 will drop, the Judson valve will close, and the pressure on the lower side of the piston 52 will be exhausted to the atmosphere. The valve 49 65 will not close, however, until the pressure

in the pipe line 6 and 65 has fallen to the point at which the spring 59 will overcome the pressure of the fluid in the cylinder 62 which is slightly above operating pressure, so that the auxiliary pump will be operated 70 until the fluid pressure in pipe line 8 is practically at operating pressure and the excess head is removed so that the main pump may start.

In the modified form of pumping unit 75 shown in Fig. 7, the pipe 8 connects with a central down pipe 77 which conducts a flow of operating fluid to a main pump 78 which forces the liquid up in outer riser 82 against an umbrella top 83 and into an auxiliary tank 84 from which the liquid or material pumped flows through a pipe 85 into a reservoir as 30. In this form of pumping unit, the pipe 44 is connected to a pipe 79 which feeds an auxiliary pump 80 held in position 85 by a foot-piece 81 preferably attached to the down pipe 77. The operation of this form of pumping unit will be apparent for the starting pump controlling means above described will control the flow of pressure fluid 90 through the pipe 79 to the auxiliary pump 80 to remove an excess head and thereafter the pressure fluid in pipe lines 8 and 77 will flow to the main pump 78 to start the main pumping operation.

If desired, my improved pump controlling means may be applied to the pumping unit disclosed in my copending application above referred to and shown herein in Figs. 6 and 8, this pumping unit differing from the form shown in Figs. 1 and 7 principally in that a separate supply for the auxiliary pump is not needed, the pressure fluid being conducted to both the auxiliary and main pump through a single down pipe. Referring particularly to Fig. 6, it will be noted that the pipe 8 connects with the down pipe 86 which feeds a main pump 87 and an auxiliary pump 88 mounted in the down pipe above the main pump. The liquid pumped passes upward through a riser 89 to a booster 90 and is conducted from there to the reservoir 30 by a pipe line 91, the pressure in the booster for forcing the liquid out through the line 91 being preferably controlled by a valve as shown at 92. In this form of my invention, the auxiliary pump 88 comprises preferably a casing having a threaded or other connection with the sections of the down pipe 86 as shown at 93 (Fig. 8). This casing is preferably provided with a series of apertures 94 for permitting a flow of pressure fluid from the down pipe into the liquid therearound. The flow of pressure fluid through these apertures is preferably controlled by a cylindrical valve 95 normally resting on a supporting flange 96 formed integral with the casing of the valve 88, the cylindrical valve being preferably spaced a trifle from

the ports 94 so as to permit a slight leakage of pressure fluid therethrough to keep the ports clean and assist the main pump 87 in elevating the liquid to be pumped. Any form 5 of valve controlling means may be used but I preferably employ a hollow valve rod 97 connected to the cylindrical valve 95 by a plurality of radially disposed webs 98 and connected to the valve controlling rod 53 10 by a sleeve 97'. As is apparent, the upward movement of the valve control rod 53 under the influence of the pressure fluid admitted to the lower part of the cylinder 51 as above described, will elevate the cylindrical valve 15 member 95 and thereby permit a free flow of operating fluid through the apertures 94 to blow off the excess head. When this excess head has been removed, the rod 53 will be permitted to fall under the influence of 20 the weight of the parts attached thereto and, the valve 88 will be closed and the liquid will be elevated by the main pump 87.

It will thus be seen that I have provided 25 an improved pumping system and an improved automatically operating controlling means for controlling a single or a plurality of pumping units to give an improved pumping operation and improved control 30 of a pumping system. It will further be noted that the pumping system is automatically operated to remove an excess head and permit the starting of a main pumping element. If a plurality of pumping units are 35 used, it will be noted that my improved pump controlling means operates to control the pumping units efficiently and if desired successively so that when the water is at a low stage in the reservoir, a large number 40 of the pumping units will be operating to fill the reservoir rapidly and that as the water in the reservoir reaches a higher stage only a small part of the pumping units will be operated.

45 While I have in this application specifically described several embodiments which my invention may assume in practice, it is to be understood that these forms are used 50 for purposes of illustration only and that the invention may be modified and embodied in various other forms without departing from its spirit or the scope of the appended claims.

55 What I claim as new and desire to secure by Letters Patent is:

1. In a pumping system, a source of fluid pressure, a fluid operated pumping means, a fluid flow controlling means between said source and said pumping means, a reservoir 60 receiving the liquid pumped by said pumping means, said reservoir being so constructed that the liquid surface therein is exposed only to atmospheric pressure, a fluid pressure controlling means, and means controlled by the liquid level in said reservoir

voir for controlling said flow controlling means.

2. In a pumping system, a source of fluid pressure, a plurality of serially operative pumping means, a reservoir receiving the 70 discharge therefrom, a fluid flow controlling means between said source and one of said pumping means, and means controlled by the level of material in said reservoir for controlling said flow controlling means. 75

3. In a pumping system having means whereby a liquid level is obtainable and which level is adapted to be changed by a pumping operation, a source of fluid pressure, a plurality of serially operative pumping means, a fluid flow controlling means between said source and one of said pumping means, and means controlled by said level for controlling said flow controlling means. 80

4. In a pumping system, a source of fluid pressure, a plurality of serially operative pumping means, a fluid flow controlling means between said source and one of said pumping means, a fluid pressure controlling means between said source and said last 85 named pumping means, a reservoir for receiving the material from said plurality of pumping means, and means controlled by the level of material in said reservoir for controlling said flow controlling means. 90

5. In a pumping system, a source of fluid pressure, a plurality of serially operative pumping means, fluid flow controlling means between said source and said pumping means, a reservoir for receiving the material from said pumping means, and means controlled by the level of the material in 100 said reservoir for controlling said controlling means.

6. In a pumping system having means whereby a liquid level is obtainable and which level is adapted to be changed by a pumping operation, a source of fluid pressure, a plurality of serially operative pumping means, fluid flow controlling means between said source and said pumping means, and means controlled by said level for controlling said controlling means. 105

7. In a pumping system, a source of fluid pressure, a plurality of serially operative pumping means, fluid flow controlling means between said source and said pumping means, a fluid pressure controlling means between said source and said last named pumping means, a reservoir for receiving the material from said pumping means, and means controlled by the level of the material in 110 said reservoir for controlling said flow controlling means. 115

8. In a pumping system, a source of fluid pressure, a fluid operated pumping means effective at different depths, a reservoir for receiving the material pumped, and means controlled by the level of material in said reservoir for controlling the flow of fluid 125 130

- from said source to said pumping means.
9. In a pumping system having means whereby a liquid level is obtainable and which level is adapted to be changed by a pumping operation, a source of fluid pressure, a fluid operated pumping means effective at different depths, and means controlled by said level for controlling the flow of fluid from said source to said pumping means.
10. In a pumping system, said fluid control means being disposed between said pumping means and source of pressure.
11. In a pumping system, a source of fluid pressure, a fluid operated pumping means effective at different depths, fluid pressure reducing means, a reservoir for receiving the material pumped, and means controlled by the level of material in said reservoir for controlling the flow of fluid from said source to said pumping means.
12. In a pumping system having means whereby a liquid level is obtainable and which level is adapted to be changed by a pumping operation, a source of fluid pressure, a fluid operated pumping means effective at different depths, fluid pressure reducing means, and means controlled by said level for controlling the flow of fluid from said source to said pumping means.
13. In a pumping system, an air lift pump, a reservoir to which said air lift pump discharges continuously during its operation and in which the liquid level varies directly as the pump discharge and inversely as the quantity of liquid used from said reservoir, a controlling means for said air lift pump governed by the liquid level in said reservoir, and fluid pressure regulating means between said pumping means and said controlling means.
14. In a pumping system, an air lift pump, a reservoir to which said air lift pump discharges continuously during its operation and in which the liquid level varies directly as the pump discharge and inversely as the quantity of liquid used from said reservoir, a controlling means for said air lift pump governed by the liquid level in said reservoir, and fluid pressure reducing means between said pumping means and said controlling means.
15. In an air lift pumping system, a fluid operated pumping means comprising a main air lift pump and an auxiliary air lift pump, separate supply lines leading to said pumps, a main supply pipe feeding both of said lines, a controlling means for said pipe, and a pressure regulating means in said pipe.
16. In an air lift pumping system, a fluid operated pumping means comprising a main air lift pump and an auxiliary air lift pump, separate supply lines leading to said pumps, a main supply pipe feeding both of said lines, a controlling means for said pipe, and a pressure regulating means in said pipe.
17. In an air lift pumping system, a fluid operated pumping means comprising an up-pipe, main and auxiliary air lift pumps in said up-pipe, separate fluid supply means for said pumps, a controlling means for both of said supply lines, a controlling means for the supply line to said auxiliary pump, and a pressure regulating means.
18. In an air lift pumping system, a fluid operated pumping means comprising an up-pipe, main and auxiliary air lift pumps in said up-pipe, separate fluid supply means for said pumps, a controlling means for both of said supply lines, a controlling means for the supply line to said auxiliary pump, and a pressure regulating means between said controlling means.
19. In an air lift pumping system, an up-pipe, main and auxiliary air lift pumps communicating with said up-pipe at different levels, separate supply means for said pumps, a controlling means for both of said pumps, a controlling means for said auxiliary pump, and a pressure reducing means.
20. In a pumping system, a fluid operated pumping means comprising a riser pipe and a plurality of pumping means cooperating therewith, fluid supply means leading to said pumping means, a fluid flow controlling means, and a fluid pressure reducing means between said pumping means and said controlling means for maintaining a predetermined difference in pressure between said pumping means and said controlling means during the operation of said pumps, but automatically operating to permit an increase in pressure at the pumps when said pumps are rendered inoperative.
21. In a pumping system, a fluid operated pumping means comprising a riser and a pump therein, a fluid flow controlling means governing the supply of fluid to said pump, and a fluid pressure reducing means between said pumping means and said controlling means operative during operation of said pump to maintain a supply of air at reduced pressure to said pump but automatically operative to permit the building up of pressure at said pump when said pump is inoperative.
22. In an air lift pumping system, a riser pipe, main and auxiliary air lift pumps operating therewith, separate supply means leading to said pumps, a main supply pipe supplying fluid to each of said first mentioned supply pipes, an auxiliary pump controlling means interposed between said main

supply pipe and the supply pipe leading to said auxiliary pump, and an automatic pressure regulating means on the supply pipe ahead of the connection between the pipe leading to the auxiliary pump and the main supply pipe.

23. In a pumping system, a source of fluid pressure, a fluid operated pumping means effective at different depths, a reservoir for receiving the material from said pumping means, means responsive to variations in the level of the material in said reservoir for varying the output of said pumping means, and pressure regulating means between said responsive means and said pumping means.

24. In a pumping system, a source of fluid pressure, a fluid operated pumping means effective at different depths, means responsive to variations in the level of the material which is affected by the pumping operation for varying the output of said pumping means, and pressure regulating means between said responsive means and said pumping means for controlling one of said pumps.

25. In a pumping system, a source of fluid pressure, a main pump, an auxiliary pump, means for controlling said auxiliary pump, a reservoir for receiving the material from said pumps, and means controlled by the level of the material in said reservoir for controlling the flow of fluid from said source to said pumps.

26. In a pumping system having means whereby a liquid level is obtainable and which level is adapted to be changed by a pumping operation, a source of fluid pressure, a main pump, an auxiliary pump, means for controlling said auxiliary pump, and means controlled by said level for controlling the flow of fluid from said source to said pumps.

27. In a pumping system, a source of fluid pressure, a main pump, an auxiliary pump, means for controlling said auxiliary pump, a reservoir for receiving the material from said pumps, and means controlled by the level of the material in said reservoir for controlling the flow of fluid from said source to said pumps and pressure regulating means between said flow controlling means and auxiliary pump controlling means.

28. In an air lift pumping system, a storage reservoir, a riser pipe discharging thereto, a plurality of air lift pumps disposed at different levels in operative relation with respect to said riser pipe, a common source of operating fluid supply for said several pumps, means for controlling a pump above the bottom one and operative to permit operation thereof only when the submergence of the bottom pump is such that the liquid static head is in excess of the normal operating pressure for said bottom pump, and means for controlling all of

said pumps controlled by the level of the liquid in said storage reservoir.

29. In an air lift pumping system, a storage reservoir, a plurality of riser pipes each disposed in a separate well and discharging into said reservoir, a plurality of air lift pumps disposed at different levels in operative relation with respect to each of said riser pipes, a common source of pressure for the pumps, in each of said wells, controlling means for the pumps in each of said wells comprising means for controlling a pump above the bottom one therein and operative to permit operation thereof only when the submergence of the bottom pump is in excess of its capacity, and a plurality of means each controlling the pumps in one of said wells serially controlled by the liquid level in said storage reservoir.

30. A pumping system having pumping means provided with discharge ports which are continuously open, means for discharging fluid through continuously open ports of said pumping means to discharge an excess and normal head, said latter means including means for generating independently of said excess head a fluid pressure in excess of that required for discharging said normal head and adapted to cause discharge of the excess head, and means whereby a pressure less than the excess pressure is used to discharge said normal head.

31. A pumping system having foot piece mechanism provided only with continuously open discharge ports, means for discharging actuating fluid through said mechanism to pump an excess and normal head, means for generating independently of said excess head a fluid pressure in excess of that required for discharging said normal head and adapted to cause discharge of the excess head, and means whereby a pressure less than the excess pressure is used to discharge said normal head, said generating means having at least a part of its operation common to the generation of both pressures.

32. A pumping system adapted to pump an excess and normal head, foot piece mechanism having continuously open discharge ports, means for generating independently of said excess head a fluid pressure in excess of that required for discharging said normal head and adapted to cause pumping of the excess head by discharging said fluid pressure through continuously open ports of said mechanism, means whereby a pressure less than the excess pressure is used to discharge said normal head, and means common to the conduction of either fluid pressure for discharging either head.

33. A pumping system adapted to pump an excess and normal head, foot piece mechanism having continuously open discharge ports, means for generating independently

- of said excess head a fluid pressure in excess of that required for discharging said normal head and adapted to cause pumping of the excess head by discharging said fluid pressure through continuously open ports of said mechanism, means whereby a pressure less than the excess pressure is used to discharge said normal head, and means whereby the pressure fluid which is subjected to a normal and excess pressure can be discharged at a common pump level.
34. A pumping system comprising a plurality of serially operative pumping means, means whereby a plurality of different fluid pressures can be had simultaneously, and means whereby each of said pumping means is caused to be operated at different pressures.
35. A pumping system comprising pumping means having discharge ports which are always open, means for generating a fluid pressure, fluid expansion means through which said pressure fluid flows, and means for effecting a plurality of different pumping operations by discharging said fluid only through said continuously open ports.
36. A pumping system comprising pumping means having discharge ports which are always open, means for generating a fluid pressure, fluid expansion means through which said pressure fluid flows, and means for effecting flow of said fluid in a plurality of directions whereby said fluid is discharged only through said continuously open ports, said flow being dependent upon the level of the material being pumped.
37. A pumping system adapted to pump an excess and normal head, foot piece mechanism having continuously open discharge passage forming means, means for generating independently of said excess head a fluid pressure in excess of that required for discharging said normal head, means automatically cooperating with said excess pressure to allow said excess head to be pumped by discharging said fluid pressure through said continuously open means, and means whereby a pressure less than the excess pressure is used to discharge said normal head.
38. A pumping system adapted to pump by fluid pressure an excess and normal head from a well, means for controlling the fluid pressure therefor disposed entirely substantially at the surface of said well, said latter means including means for generating independently of said excess head a fluid pressure in excess of that required for discharging said normal head, means cooperating with said excess pressure for blowing an excess head and dependent upon the existence of the latter for initial operation, and means whereby a pressure less than the excess pressure is used to discharge said normal head.
39. A pumping system comprising pumping means having only continuously open discharge ports, a source of pressure fluid, connecting means therebetween having means for obtaining simultaneously different pressures therein during pumping of a relatively low head, and fluid actuated means responsive to an increase in the submergence head for controlling the pump thereof.
40. A pumping system comprising pumping means, a source of pressure fluid, connecting means therebetween having means for obtaining simultaneously different pressures therein during pumping of a relatively low head of liquid, means for controlling flow of fluid pressure to said pumping means wholly disposed above any point of discharge of said fluid pressure, and fluid actuated means responsive to an increase in the submergence head to pump automatically said head.
41. A pumping system comprising pumping means, a source of pressure fluid, means whereby during pumping of a normal head of liquid the pressure of the fluid after flowing from said source is reduced, said reduced pressure approaching the source pressure upon increase of the submergence head, and means automatically responsive to the increasing of said head to pump the same, said latter means being disposed entirely above the uppermost point of fluid pressure discharged in said pump.
42. A pumping system, a source of pressure fluid, means for pumping an excess and normal head including means for reducing during pumping of a normal head the pressure of the fluid after flowing from said source and for automatically pumping an excess head when said reduced pressure is unable to pump said normal head, said pumping means including a continuously open discharge passage through which the pressure fluid flows for pumping said excess head.
43. A pumping system, a source of pressure fluid, means for controlling said pressure fluid disposed entirely at the uppermost portion of said system, means for pumping a varying submergence head including means for reducing during pumping of a normal submergence head the pressure of the fluid after flowing from said source and for automatically controlling fluid supply from said source during pumping of a submergence head above normal which is too great to be pumped by the normal reduced pressure.
44. A pumping system comprising a source of pressure fluid, means for pumping a normal and excess head including a foot piece having a continuously open passage through which pressure fluid is discharged for pumping said excess head, said means also including means whereby upon pumping of the normal head the pressure of the

fluid after flowing from said source is reduced, said reduced pressure approaching the source pressure upon increase of the submergence head, and means actuated by said reduced pressure for further controlling the fluid supply.

45. A pumping system comprising a source of pressure fluid, means for pumping a normal and excess head including means whereby upon pumping of the normal head the pressure of the fluid after leaving said source is reduced, said pumping means including discharge mechanism having only relatively fixed elements which are disposed within the liquid to be pumped, said reduced pressure approaching the source pressure upon increase of the submergence head, and means actuated by said reduced pressure for further controlling the fluid supply, said latter means including a piston and cylinder.

46. A pumping system comprising a source of pressure fluid, pumping means adapted to pump a varying submergence head, including only continuously open pressure fluid discharge ports, means for reducing the pressure of said fluid after flowing from said source to pump a normal submergence head, said reduced pressure approaching the source pressure when the submergence head increases, and a cylinder and piston therein actuated by said pressure which is increased by the increased submergence to automatically pump said increased submergence head.

47. A pumping system comprising a source of pressure fluid, means for pumping a normal submergence head at a pressure less than the source pressure during existence of the latter, said pumping means including only continuously open discharge ports, and means automatically responsive to an increased submergence head for pumping the same by fluid flowing from said source.

48. A pumping system comprising a plurality of air lifts, a single source of pressure fluid therefor, and means whereby different operating pressures for each of said air lifts can exist simultaneously.

49. A pumping system comprising a plurality of air lifts, a single source of pressure fluid therefor; means whereby different operating pressures for each of said air lifts can exist simultaneously, and automatic means for varying said operating pressures.

50. A pumping system comprising a plurality of air lifts, a single source of pressure fluid therefor, means whereby different operating pressures for each of said air lifts can exist simultaneously, and automatic means for varying said operating pressures in accordance with variations of the submergence head of each particular lift.

51. A pumping system comprising a plurality of air lifts, a supply pipe therefor,

branch pipes leading from said supply pipe to each of said air lifts, and means associated with each of said branch pipes and responsive to an increased submergence head to automatically pump the same.

52. A pumping system comprising a plurality of air lifts, a supply pipe, branch pipes leading therefrom to each of said air lifts, means for reducing the pressure fluid from said supply pipe to each of said air lifts, and means cooperating with said latter means whereby when an increased submergence takes place the same will be automatically pumped.

53. A pumping system comprising a single source of actuating pressure fluid, a plurality of air lifts, means for connecting the latter to said source including for each lift a supply pipe having a valve therein adapted to reduce the pressure of the actuating fluid after the same flows from said source, a bypass leading for each of said supply pipes, a cylinder and piston therein having communication with each of said bypasses to further control the flow of fluid from said source to said air lifts.

54. A pumping system comprising a single source of actuating pressure fluid, a plurality of air lifts, means for connecting the latter to said source including for each lift a supply pipe having a valve therein adapted to reduce the pressure of the actuating fluid after the same flows from said source, a bypass leading from each of said supply pipes, and a cylinder and piston therein having communication with said bypass to further control the flow of fluid from said source to said air lifts, said piston being actuated by an increase of the submergence head.

55. In an air lift system, a single source of actuating fluid pressure, a plurality of air lifts each having a down pipe and a supply pipe connected to said source, and fluid control valves disposed between said source and each of said down pipes for automatically controlling the flow of actuating fluid to discharge a varying submergence head.

56. In an air lift system, a single source of fluid supply, a plurality of air lifts each having a down pipe and a supply pipe connected to said source, and fluid control valves disposed between said source and each of said down pipes for automatically controlling the flow of fluid to discharge a varying submergence head, said automatic operation for each lift being independent of the other lifts.

57. An air lift control system comprising, in combination with a plurality of air lifts and a pressure line connected to supply air to said air lifts, an automatic valve included in the connection from the pressure line to each air lift, and controlling means for said valve adapted to be operated by pressure and connected to the corresponding air lift so

as to be responsive to the submergence pressure of said air lift and to open or close the valve so as to vary the supply of air therethrough and control the supply of air from the pressure line to the said air lift in correspondence with the submergence pressure thereof.

58. In combination with a plurality of air lifts and a pressure line adapted to supply the same with compressed air, a valve included in the connection from said pressure line to each air lift, pressure controlled

means for operating each of said valves and adapted to open or close the valve so as to vary the supply of the air therethrough, a connection from each air lift in the pressure controlled means for operating the valve for said air lift to effect operation of the pressure controlled means and of the valve for said air lift responsively to the submergence pressure of said air lift.

In testimony whereof I affix my signature.

HALBERT B. HALVORSEN.
